Application filed October 31, 1894. Serial No. 527,582. Term of patent 3½ years.

To all whom it may concern:

Be it known that I, GEORGE F. GREENE, a citizen of the United States, residing at Providence, in the county of Providence and State 5 of Rhode Island, have invented and produced a new and original Design for Scarf-Pins, of which the following is a specification, reference being had to the accompanying drawing, forming a part thereof.

10 The head or ornamental portion of the scarf-pin has the outline, shape and appearance of a cat, in front view, sitting on its hind legs, the hind legs extending to one side and its tail curved and extending to the other side.

A fiddle is held by its left paw and against its cheek. Its right leg is bent, arm-fashion, and its right paw holds a bow, which extends across the fiddle strings. The pin tongue extends centrally downward from said ornamental portion or head. 15 20
